UNITED STATES PATENT OFFICE.

EARL HUBER, OF CLEVELAND, OHIO, ASSIGNOR TO CHICAGO RAILWAY EQUIPMENT COMPANY, OF CHICAGO, ILLINOIS, A CORPORATION OF ILLINOIS.

LOCKING-KEY FOR BRAKE-SHOES.

1,304,049.

Specification of Letters Patent.

Patented May 20, 1919.

Application filed November 15, 1917. Serial No. 202,229.

To all whom it may concern:

Be it known that I, EARL HUBER, a citizen of the United States, and a resident of Cleveland, county of Cuyahoga, and State 5 of Ohio, have invented a new and useful Improvement in Locking-Keys for Brake-Shoes, of which the following is a specification, the principle of the invention being herein explained and the best mode in which 10 I have contemplated applying that principle, so as to distinguish it from other inventions.

The present invention relates to keys for holding brake shoes to brake heads and more 15 particularly has for its object the provision of a key which can be used with the standard brake head and shoe of the Master Car Builders' Association and which will be securely locked in position when in use so 20 that it cannot loosen and fall out as do keys of the present type. To the accomplishment of the foregoing and related ends, said invention, then, consists of the means hereinafter fully described and particularly 25 pointed out in the claim.

The annexed drawing and the following description set forth in detail certain mechanism embodying the invention, such disclosed means constituting, however, but one 30 of various mechanical forms in which the principle of the invention may be used.

In said annexed drawing:—

Figure 1 is a perspective view of my improved key; Fig. 2 is a vertical section 35 through a brake head and shoe showing my improved key in position, and Fig. 3 is a sectional view taken on the line 3—3 Fig. 2.

The drawings show a standard brake head and shoe of the Master Car Builders' Association, which is the equipment used on all 40 the railroads in this country. As shown, the brake head 1 is provided with two contact lugs 2, between which is a slot adapted to be engaged by the center lug 3 formed on 45 the rear face of the brake shoe 4. The two ends of the brake head are U shaped, which provides an opening 5 through which a key 11 may be inserted.

The two lugs 2 on the brake head 1 and 50 the center lug 3 on the shoe 4 have aligned openings 6 and 7 through which the key 11 is adapted to be passed. As shown in Fig. 2, these openings are not in direct alignment, but the rear wall 8 of the opening 7 55 through the center lug is in front of the

walls 9 of the openings 6 through the lugs on the brake head. This allows the key to contact the front walls 10 of the apertures 6 through the brake head lugs and the rear wall 8 of the aperture 7 through the lug on 60 the brake shoe, thus keeping the brake shoe tight against the forward faces of the lugs on the head.

The present key 11 is of the same general form as the key made standard by the Master Car Builders' Association, being curved 65 slightly and tapering from one end to the other. The key is provided at its outer end with a projection or lug 12 formed on the concave side 13 of the key adjacent the key 70 head 14.

The lug 12 is preferably formed by bodily bending the key near its headed end thus preserving the same thickness of metal throughout the length of the key, and enabling such jog or bend to be formed either at the time the key is forged (if such is its method of manufacture) or malleableized, or after the key is made. Thus it is possible to use old types of keys before or after they 75 are placed in service, and shape them to form the locking projection shown. This locking projection, when formed, provides anti-clinal surfaces which are adapted to cam the key in its movement both into and 80 out of engagement with the shoe, and hence the key is easily manipulated while the locking projection provides an efficient and secure lock for preventing loss or accidental 85 displacement of the key and shoe.

The key will be driven in place as usual and when forced through the openings in the lugs will be in the position shown in Fig. 2 with the projection 12 forced below the extending portion 15 of the brake shoe, 90 thus locking the key in position and preventing the accidental removal of the same.

As the key is the only lock between the shoe and the head, it will be readily seen that the loss of the key allows the brake 100 shoe to fall out. The shoe contacts with the brake head on the lugs 2 and has a clearance at the ends as shown at the points 16 which allows the shoe to rock slightly and aline 105 itself to the car wheel. This rocking movement quickly loosens the keys now in use and the only way to prevent their falling out when the car is turned over, as is customary in dumping coal cars, particularly when loading vessels, is to bend the extending end 110

of the standard key (here shown in dotted lines under the point 17 on the brake head).

By my present locking means I can use a much shorter key than is now standard, thereby effecting a saving in metal and yet the key is securely locked in position at all times. The removal of the key is a simple matter as it merely has to be sprung back sufficiently to allow the projection to pass 10 the point on the shoe and this is easily done as the rounded surface of the projection will readily come over the shoe once it is started.

Other modes of applying the principle of 15 my invention may be employed instead of the one explained, change being made as regards the mechanism herein disclosed, pro-

vided the means stated by the following claim, or the equivalent of such stated means, be employed.

I therefore particularly point out and distinctly claim as my invention:—

A locking key for brake shoes which is slightly curved and tapered and which key is also provided with a locking projection near the extremity of its thickened end, said locking projection having anti-clinal camming surfaces adapted to cam the key in its movement both into and out of engagement with the shoe.

Signed by me, this 13th day of November, 1917.

EARL HUBER.
